VENETIAN BLIND CONSTRUCTION

Peter H. Kuyper, Pella, Iowa, assignor to Roll-Screen Company, Pella, Iowa, a corporation of Iowa

Original application March 12, 1934, Serial No. 715,148. Divided and this application September 21, 1934, Serial No. 744,923

4 Claims. (Cl. 156—17)

The object of my invention is to provide a Venetian blind construction which is simple, durable and comparatively inexpensive to manufacture, the present application being a division of my co-pending application Serial No. 715,148, filed March 12, 1934, patented March 15, 1935, No. 1,993,173.

More particularly it is my object to provide a Venetian blind structure including a housing 10 wherein substantially all of the operating mechanism, such as pulley wheels and guide wheels for raising and lowering the Venetian blind, as well as the operating members for tilting the blind structure forwardly and rearwardly, are supported and concealed.

A further object is to provide a casing having a flat bottom against which the uppermost blind slat may rest in substantially parallel position whereby the blind, when in raised position, will 20 fit snugly against the under side of the housing and eliminate any light line between the slats and the casing of the blind. The bottom wall of the casing is substantially the same width and length as are the blind slats so that when the slats are in nested position a neat appearing structure will be provided.

Still a further object is to provide a casing for concealing the operating mechanism of the Venetian blind which is rectangular in cross section 30 and which lends itself to being mounted against the head jamb of a window opening and supported by means of attachment with the side jambs of the window opening, eliminating any open spaces or "light spaces" between the casing itself and the head jamb or side jambs of the window opening. Still another object is to provide a Venetian blind in which the blind can be raised and the slats, even though inclined before the raising operation, can be automatically 40 pulled up to a horizontal position when the blind is completely raised, thus nesting the slats neatly in a level position below the horizontal bottom wall of the casing.

Heretofore the conventional Venetian blind included a supporting bar and a tipping bar positioned below the supporting bar and spaced therefrom; the slats were suspended from the tipping or tilting bar. When the slats were in raised position, then there would be a light space 45 between the supporting bar and the tipping bar as well as between the supporting bar and the head jamb of the window opening, which does not lend itself to making a neat appearing Venetian blind structure when in closed position and it has been my object to overcome and elim-

inate any light spaces between the blind slat and the support therefor.

Still a further object is to provide means for supporting the tape ladders in such position that when the slats are in closed or inclined position the slats will assume a position close to the window and at the same time in off-center relationship to the casing from which they are suspended.

With these and other objects in view my invention consists in the construction, arrangement and combination of the various parts of my device, whereby the objects contemplated are attained, as hereinafter more fully set forth, pointed out in my claims and illustrated in the accompanying drawings, in which:

Figure 1 is a perspective view of my Venetian blind structure in closed position.

Figure 2 is a similar view with the blind slats in extended or lowered position.

Figure 3 is a sectional view taken on the line 3—3 of Figure 1.

Figure 4 is a sectional view taken on the line 4—4 of Figure 2, the dotted lines illustrating positions of the slats when partially inclined.

Figure 5 is a top plan view of the casing for the Venetian blind and the operating and supporting mechanism therein.

Figure 6 is an enlarged sectional view illustrating the blind slats in fully inclined or closed position.

Figure 7 is a perspective view of one end of the casing illustrating the spring catch and support for the casing.

Figure 8 is a top plan view of one end of the housing, substantially enlarged; and

Figure 9 is a diagrammatic view showing the parts in Figure 6 adjusted to a position where the blind is nearly completely raised.

On the accompanying drawings I have used 40 the reference character A to indicate generally a window opening which includes side jambs 10 and a head jamb 12. My Venetian blind structure includes a casing B having a bottom 14, a front wall 16 and a rear wall 18. The casing 45 B is formed of sheet metal bent into the form of a channel and the upper ends of the walls 16 and 18 are bent inwardly and downturned as at 20 and 22 to provide a reinforcing edge for the walls 16 and 18 and to give rigidity to 50 the entire casing. On each end of the casing a spring catch 24 is secured to the inside of the wall 18 by spot welding, or any other suitable manner. The catch 24 has a single engaging piece 26 which projects beyond and forward. 55

ly of the front wall 16, as clearly illustrated in Figure 7 of the drawings.

In order to support the casing relative to a window opening, I provide a bracket support 28 having a bottom support 30 and a side wall 32. The side wall 32 is provided with openings 34 through which screws or the like 36 may project for mounting the bracket support 28 relative to a window opening in the side jambs 18 thereof. The supporting bracket 28 includes a narrow front wall 38 against which the spring catch 24 rests.

The casing B is slid onto the bottom 30 of the supporting brackets 28 and the spring catches 24 retain the casing B relative to the supporting brackets 28 under a yielding tension. The casing B may be quickly and easily removed from its supports by pulling the spring catch inwardly or towards the casing B. The position of one of the spring catches 24 is indicated in dotted lines in Figure 8 and when in this position the housing can be removed from the supporting brackets.

Within the casing B are mounted brackets 40. Rotatably mounted within the brackets 40 are a pair of rollers or shafts 42. Between the shafts 42 and supported in each bracket 40 are pulley wheels 44. The two shafts are geared together by a train of gears 46. A shaft 48 is connected to one of the train of gears 46 and has a drum or the like 50 secured thereto. A tilting cord 52 is connected to the drum 50 and has its free ends extending through an opening 54 formed in the front wall 16 of the casing B. A roller 55 is provided for the cord 52 to reduce friction.

Knobs or the like 56 are secured to the free ends of the tilting cord 52. Pulling of either of the ends of the cord 56 will impart rotation to the drum 50 and thereby to the train of gears 46 and the shafts 42 in the same direction. The parts just described are clearly illustrated in my co-pending application Serial No. 715,148.

Secured to each of the shafts 42 are tape ladders C. The tape ladders C are flexible, preferably being formed of a woven cloth-like material. Each of the tape ladders C includes rungs or supporting pieces 58, which are connected to the tapes 60. Secured to the lower end of the tape ladders is a lower rail 62. Mounted and supported upon each of the rungs 58 of the tape ladders C is a blind slat 64. Extending through slots in the slats 64 and secured to the lower rail 62 are a pair of cords 66, which may be properly termed raising and lowering cords. The cords 66 are normally hidden from view by the tape ladders C. The cords 66 extend over the pulley wheels 44 and pass through a guide and retaining device D and project downwardly through the casing B.

Secured to the guide and retaining device D is a control cord 68, which may be operated for causing the retaining device to grip the cords 66 and retain the Venetian blind in its raised position.

When it is desired to incline the blind slats either forwardly or rearwardly, the cords 66 are engaged and through them the drum 50 is rotated in either direction with the result that one tape of each tape ladder will wind onto a shaft 42 while the other one will unwind therefrom, thus causing the rungs 58 to move to an inclined position with the slats resting thereon likewise moving to an inclined position. In Figure 4 the slats have been shown only partially inclined by dotted lines.

When it is desired to move the slats to a completely closed position, such as shown in Figure 6, then continued rotation of the shafts 42 will cause one tape closest to the window opening to wind onto one shaft 42 and the other tape to unwind and become somewhat loose so that the entire Venetian blind will actually be suspended from a single tape of the tape ladder. The tendency will be for the slats to assume a position close to the window opening.

It will be noted from an examination of Figures 1 and 3 that the bottom 14 of the casing is substantially the same width as the slats 64 and it will also be noted that the slats 64 are capable of being positioned close to and against the under side of the casing B. It is desirable to avoid any light spaces between the casing B and the slats when they are in raised position. The casing itself, of my Venetian blind structure, rests against the under side of the head jamb 20 and there is no light space therebetween. My blind structure lends itself to being positioned within the window opening and not interfering with the architectural beauty.

I have found from actual experience in the commercial production of my blind that it is desirable in residences to provide a blind structure that does not have exposed any of the hardware or supporting brackets of the blind and with my blind structure the slats and tape ladders are suspended from the casing B with all of the operating mechanism of the blind mounted within the casing.

In Figure 9 I have shown how the slats can all be pulled up close together when raising the blind as in Figure 6 and then automatically swung to a horizontal nested position, Figure 9 illustrating the slats swung about half way to such nested position or assuming a position intermediate the positions shown in Figures 6 and 3. 40

It is obvious that with the slats tipped to any angle when the raising rope 66 is manipulated to raise the blind the bottom rail 62 will first pick up the slats and then exert a tipping force on the slats as the rope 66 is further pulled thereafter. This will swing the slats in the direction of the arrow a in Figure 9 and finally pull them up to the position of Figure 3 irrespective of the angle of the slats before they are pulled to their raised position. This feature of the invention 50 is quite desirable as, for the sake of neatness, the slats should be horizontal when they are completely nested, instead of being at an angle, and this is accomplished in my construction without the necessity of adjusting the slats to their 55 horizontal position before raising them.

Some changes may be made in the construction and arrangement of the parts of my device without departing from the real spirit and purpose of my invention, and it is my intention to cover 60 by my claims any modified forms of structure or use of mechanical equivalents, which may be reasonably included within their scope.

I claim as my invention:

1. In a Venetian blind head member, a casing, 65 means within said casing for suspending a Venetian blind comprising plural tape ladders and slats and means within said casing for tipping said slats, said last means being adjustable and in one position of its adjustment supporting one side of each tape ladder loosely and the other side of each tape ladder taut, whereby the slats will assume a position of suspension adjacent the side of each tape ladder that is taut to effect maximum closure of the slats.

2. In a Venetian blind support for a Venetian blind having tape ladders and slats, a casing, means therein for suspending the two sides of said tape ladders for either holding the blind slats in a horizontal plane or raising one side of the tape ladders while lowering the other side thereof to effect tipping of said slats, said blind, when said means is adjusted to position for closure thereof, being suspended in a position out 5 of the normal vertical plane of the blind and by one side only of said tape ladders.
3. In a Venetian blind structure, a supporting casing adapted for mounting adjacent one side of a window frame, means on said support for suspending the tapes of a Venetian blind having 10 tape ladders and slats in a normal position directly below said support and spaced from said window frame and for raising one side of said tape ladders while lowering the other side there- 15
- of to effect tipping of said slats, said blind, when said means is adjusted to position for closure thereof, being suspended by one side of said tape ladders only and in a position with said Venetian blind out of alignment with its normal position and closely adjacent said window frame.
4. In a Venetian blind structure, a casing, supporting means therein connected with one side of the tape ladders of a Venetian blind and a second supporting means therein connected with 10 the other side of said tape ladders for adjusting the angle of the slats of a Venetian blind, said first means when in one position supporting one side of each tape ladder loosely and said second means supporting the other side taut whereby 15 the slats will assume a position of suspension vertically beneath said second means.

PETER H. KUYPER.
